FIG.1

FIG.2

FIG.3

FIG. 1 is a perspective view of an automobile rain visor for drive-in theatres, embodying my new design,

FIG. 2 is an extended lay out view thereof, and

FIG. 3 is a front elevation view of the extended form thereof.

The vehicle fragmentarily shown in broken lines in FIG. 1 is included for illustrative purposes only.

This is a continuation-in-part of design application Ser. No. D. 19,923, filed Nov. 4, 1969, now Patent No. D. 219,440.

I claim:

The ornamental design for an automobile rain visor for drive-in theatres, substantially as shown and described.
